(57) **CLAIM**

The ornamental design for a metal hook for paper hanger, as shown and described.

DESCRIPTION

FIG. 1 is a front perspective view of a metal hook for paper hanger showing our new design;

FIG. 2 is a rear perspective view thereof;

FIG. 3 is an enlarged front elevation view thereof;

FIG. 4 is an enlarged rear elevation view thereof;

FIG. 5 is an enlarged right side elevation view thereof;

FIG. 6 is an enlarged left side elevation view thereof;

FIG. 7 is an enlarged top view thereof; and,

FIG. 8 is an enlarged bottom view thereof.

The broken lines shown represent unclaimed subject matter and form no part of the claimed design.
